(57) **CLAIM**

The ornamental design for a hammer head, as shown and described.

DESCRIPTION

FIG. 1 is a left, front, perspective view of a hammer head including a hammer head in accordance with the present design;

FIG. 2 is a left, side view of the hammer head of FIG. 1; FIG. 3 is a right, side view of the hammer head of FIG. 1; FIG. 4 is a rear view of the hammer head of FIG. 1; FIG. 5 is a front view of the hammer head of FIG. 1; FIG. 6 is a top view of the hammer head of FIG. 1; and, FIG. 7 is a bottom view of the hammer head of FIG. 1. The broken lines shown in the drawings illustrate portions of the hammer head that form no part of the claimed design.
